Inventor

Ernest L. Emery

Clarence A. O'Brien
Attorney

UNITED STATES PATENT OFFICE.

ERNEST LOYD EMERY, OF CHARLESTON, SOUTH CAROLINA.

COLLAPSIBLE TUBE DISPENSER.

Application filed November 7, 1927. Serial No. 231,610.

My invention relates to collapsible tube dispensers, the same being especially adapted for dispensing the contents of paint tubes, tooth paste tubes, and in fact any materials 5 contained in collapsible tubes.

It is a well known fact that the handling of collapsible tubes containing paint, or tooth paste is quite undesirable, due to the fact that a considerable amount of the contents frequently become smeared on the outer side of 10 the tube which must be touched by the user in order to compress the tubes.

The main purpose of my invention is to eliminate entirely this situation by providing 15 a device in which one or more collapsible tubes containing various contents may have their contents easily dispensed without the hands of the user coming in contact with the exterior of the tubes.

20 The main object of my invention is to provide a device wherein at least one pair of rollers are employed in contact with each other, and between each of which the bottom end of a collapsible tube is adapted to be inserted for the purpose of dispensing the 25 contents thereof.

Still another object resides in the means employed whereby each pair of these rolls may be actuated independently of the other 30 pair.

A further object resides in the tensioning means whereby the rolls are normally maintained in very snug contact with each other. 35

Other various novel objects and advantages will become apparent as my device is better 40 understood from the specification and claims to follow.

In the drawing:

Figure 1 is a side elevation of my device in partial sectional view disclosing the manner in which one of the lower rolls is mounted for rotation, and

45 Fig. 2 is a vertical sectional view taken substantially on the line 2—2 of Fig. 1, and looking in the direction of the arrows.

For a more detailed description of my invention, I now refer to the drawings, in which like numerals designate like parts of 50 the same. A pair of standards 1 and 2, respectively, are mounted perpendicularly on suitable base plates 3 and 4 respectively. Jour-

naled through the respective standards adjacent their upper portions are the free ends of a stationary shaft 3.

Rotatably mounted on this shaft, are rolls 55 4, 5 and 6 respectively. It is preferable that these rolls be constructed of wood or other relatively cheap material, while the outer surface is covered with a resilient material, such as rubber. To one end of each of said rolls, 60 a gear wheel 7 is fixedly associated. Spacing collars 8 are disposed between the inner side of the respective standards, and the ends of the respective rolls, while additional spacing collars are disposed between the gears 7 and 65 the respective end portions of the adjacent rolls.

The end portions of a rod 9 are fixed in the respective standards 1 and 2 respectively, at the lower portion thereof. Arranged upon 70 this rod 9, is a plurality of cylindrical shaped collar members 10, each of said cylindrical collars being formed with a longitudinal bore therethrough, said bore being of elongated extent in cross section, and through which 75 the rod member is adapted to extend.

Mounted for rotation upon opposed end portions of the collars 10, are lower rolls 11, 12 and 13 respectively. These rolls are constructed in substantially the same manner 80 as are the rolls 4, 5 and 6, respectively, mounted on the shaft 3. The lower rolls are adapted to be disposed directly under the upper rolls, and adapted to snugly engage each other. 85

Connecting the respective standards adjacent the lower portions thereof, is a bar 14. Depending from each of said cylindrical collars 10 is a stem 15, the lower end portion of which is adapted to screw thru suitable openings in the bar 14. Arranged around each of 90 said stems 15, and disposed between the respective collars and the bar 14, is a coiled spring 16.

Journalized for rotation at the upper portion of the standard, is a squared shaft 17, one end portion of which projects beyond the standard 2. To this projecting end portion of the shaft 17 is secured a hand wheel 18.

Adapted for rotation with the shaft 17 100 and slidably mounted upon the same, is a pinion gear 19. This pinion gear 19 is adapted

to be shifted upon the squared shaft 17, whereby it may be brought into meshed relation with any one of the gears 7.

Located above the squared shaft 17 and 5 having their adjacent end portions secured in the respective upper portions of the standards 1 and 2 respectively, is a pair of rod members 20 disposed in a horizontal plane.

A gear shifting body 21 is formed with inwardly bent portions 22 adapted to encircle the respective rod members 20, and upon which the gear shift body is adapted for slideable movement. At one end portion of this body 21 is a pair of spaced depending yoke members 23, the leg portions of said yoke members adapted to engage opposite sides of the pinion 19. At the opposite end portion of the gear shift body 21, a pair of depending indicating pointers 24 are provided. The 15 pointed portions of these members 24, are adapted to be disposed approximately directly over the center portion of one of the rollers when the pinion gear 19 carried by the gear shift body 21 is in meshed relation with one 20 of the gear wheels 7.

The handle 25 may be provided at the top of the body 21, whereby the same may be more conveniently moved on the rods 20.

By inserting the tapered bottom portion 29 of a collapsible tube, between each pair of rollers, at their point of contact, and by moving each of the rolls 4, 5, and 6 respectively, the tube will be maintained in position. For example, to dispense the contents of a tube inserted between the rollers 4 and 11, respectively, of my device, as is clearly shown in Fig. 1 of the drawing, the gear shift body 21 is slid along the bars 20 until the pointer 24 is directly over the center portion of the roll 4. 35 At this point, the pinion gear 19 is in meshed relation with the gear 7, and by rotating the hand wheel 18, the pinion 19 will cause the gear on the roll 4 to rotate thusly causing the tube to be fed through and between the respective upper and lower rolls.

In order to maintain the lower roll in proper snug contact with the upper roll, or with the under side of the collapsible tube when the same is disposed between the rolls, I provide the novel tensioning means disclosed in the drawings. The lower rolls are mounted for rotation on the cylindrical collars 10, which are formed with longitudinal bores therein of elongated extent in cross section.

The rod 9 extending through the collars guide the up and down movement of same, due to the tensional pressure of the coiled springs 16. When the end of a collapsible tube is disposed between the rolls, the lower roll will be forced downwardly somewhat, thusly causing the compression of the coiled

springs, which tensionally support the cylindrical collars upon which that particular roll is rotatable.

Having thus described my invention, what I claim as new is:—

1. In a collapsible tube dispensing device of the character described, a pair of upstanding supports, an upper and a lower shaft, said shafts connecting said supports, spaced rolls 70 rotatable on said upper shaft, collar members loosely arranged upon the lower shaft, rolls mounted for rotation upon said collars, stem members depending from said collars, and spring elements associated with said stems for 75 normally maintaining the collars forced upwardly.

2. In a collapsible tube suspension device of the character described, a pair of upstanding supports, an upper and a lower shaft on 80 said supports, spacing rolls rotatably mounted on said upper shaft, a plurality of collars arranged on the lower shaft, said collars being formed with longitudinal bores of elongated cross section, rolls arranged on said collars 85 for rolling contact with the upper rolls, and tensional means associated with said collars for urging the lower rolls upwardly.

3. In a collapsible tube suspension device of the character described, a pair of upstanding supports, an upper and a lower shaft on 90 said supports, spacing rolls rotatably mounted on said upper shaft, a plurality of collars arranged on the lower shaft, said collars being formed with longitudinal bores of elongated cross section, rolls arranged on said collars for rolling contact with the upper rolls, and tensional means associated with said collars for urging the lower rolls upwardly, and means 95 for rotating the said upper rolls individually.

4. In a collapsible tube suspension device of the character described, a pair of upstanding supports, an upper and a lower shaft on 100 said supports, spacing rolls rotatably mounted on said upper shaft, a plurality of collars arranged on the lower shaft, said collars being formed with longitudinal bores of elongated cross section, rolls arranged on said collars for rolling contact with the upper rolls, and tensional means associated with said collars for urging the lower rolls upwardly, and means 105 for rotating the said upper rolls individually, said last mentioned means consisting in providing each of the upper rolls with a gear, a rotatable shaft mounted at the upper end of the supports, and a pinion on said shaft engageable selectively with the several gears, said pinion being adapted for rotation by said shaft.

In testimony whereof I affix my signature.

ERNEST LOYD EMERY.
